Robert Briggs

United States Patent Office.

ROBERT BRIGGS, OF PHILADELPHIA, PENNSYLVANIA.

Letters Patent No. 98,020, dated December 21, 1869.

IMPROVED MACHINE FOR MAKING FERRULES.

The Schedule referred to in these Letters Patent and making part of the same.

Be it known that I, ROBERT BRIGGS, of Philadelphia, in the county of Philadelphia, and State of Pennsylvania, have invented certain new and useful Improvements in the Manufacture of Sockets or Ferrules of Wrought-Iron, and in Machines for Making the same; and I do hereby declare the following to be a full and exact description thereof, reference being had to the accompanying drawings, making a part of this specification, in which—

Figure 1 is a perspective view of a tube of metal, exhibiting a socket or ferrule cut from the end of the same.

Figure 2 is a side view of the machine which I propose to use for cutting off and sound-welding the socket or ferrule.

Figure 3 is an end-view of the same machine, showing the gearing for driving the rollers.

Figure 4 is an opposite end view of the same machine, showing the rollers, mandrel, &c.

Figure 5 is a top view of the same machine.

The same letters indicate similar parts upon the several views, as follows:

A A is the tube to be cut off.

B B is the socket or ferrule.

C C, the bed-plate.

D D the stands.

E' E E E, the driving-gear wheels; E', the central wheel.

F F, the pulley.

G G G', the shafts, G' being the upper shaft.

H H H', the rolls, H' being the upper roll.

I I, the cutter.

J J, the mandrel.

j, the collar of the mandrel.

j, the shoulder of the mandrel.

K, the withdrawing-lever.

K', the hand withdrawing-lever.

k, the connecting-link.

L, the lever to relieve the mandrel; l is the arc to lock this lever.

M, the treadle to operate the top roller.

m m, the side-connecting links, which join the box or bearing of the top roller with the treadle.

N, the weight.

O, the ball-box or bearing for one end of the top roller-shaft.

P, the sliding box or bearing at the other end of the top roller-shaft.

Q, the arc in which the lever K moves.

q, notch to lock K'.

To enable others skilled in the art to make and use my invention, I will proceed to describe the same.

The usual and customary way of making iron sockets or ferrules has been to take a strip of metal, of suitable width and length; to scarf or bevel off the ends, and turn them up together; to join the ends at a weld-

ing-heat, by a hammer, upon the beak of an anvil; and to finish by swaging or rounding and sizing upon a mandrel, in a hollow bed or die, by the application of a top-swage or die with a hammer.

In my improved manufacture, I take a piece of tube, which has been either but or lap-welded, and at a welding-heat place the end of it upon and against the shoulder of the projecting mandrel, in the interstice between the three rollers of my machine. Then, by the application of the foot upon the treadle, the top roller is brought down upon the end of the tube, the cutter making an indentation at the proper place for the length of the socket, and by the continued compression from the treadle, the rollers having a transverse motion given them, as shown on the drawing, the socket is cut off, sized, by closing down upon the mandrel, and great uniformity of thickness of metal of the socket insured. After the socket is cut off the tube, the mandrel is withdrawn by the withdrawing-lever K, through the hand withdrawing-lever K' and the connecting-link k.

Upon relieving the treadle, the weight which counterbalances it and the top roller and its bearings, lifts the roller, when, upon replacing the mandrel to its projection for making the next socket, the finished socket will be expelled from between the rollers.

It would be practicable to swage the end of a tube upon a mandrel by a hammer, which should have cutters placed in the bits or dies, to cut off the end. The hammer could be similar to an ordinary tilt-hammer, or like the reciprocating hammer known as a Radus forge, the mandrel being drawn out by a withdrawing-lever behind, in a way similar to that hereinbefore described for the three-roller machine; but I think that sockets or ferrules of the kind I have invented can be made more satisfactorily and cheaply by the three-roller machine than otherwise.

My improved three-roller machine, for the manufacture of sockets or ferrules, consists (the form in which I prefer to construct it) of the bed-plate C C and the stands D D, which constitute the frame-work for carrying the shafts G G G'.

These shafts have at one (or the driving) end, the train of gear-wheels E E E, which are driven by the central wheel E', (this wheel may be an external gear-wheel, with the three others around it; or an internal gear, including or surrounding the three others.)

The central wheel E' has upon the same shaft or sleeve the pulley F, to which motion can be given by a belt.

The two lower shafts, G G, run in fixed boxes or bearings in the stands D D, but the upper one, G', has a ball (or a pivot) bearing at the end next the gear-wheel E, and a sliding (or lifting) bearing at the end next the roller H'.

The shafts project beyond the frame on the front

(or working) end of the machine, and carry the rollers H H H', the first two, H H, being plain, and the third having a cutter, I, either formed upon it or placed with it on the shaft G'.

The length of the shafts is so great that the slight angular motion which it is needful to give to the upper shaft G', does not interfere with the action of the gear-wheels E E E E', nor practicably effect the parallelism of the sockets when finished, although they may vary slightly in thickness.

The lever to relieve the mandrel is hung by its centre to the front stand, D, (locked by the arc l,) and it supports the centre or fulcrum of the withdrawing-lever K. The upper end of this lever K is forked, and in the fork the mandrel J rests, the collar j' of the mandrel embracing the ends of the fork.

The mandrel is placed in the interstice of the three shafts, the front end projecting through a hole in the stand D, between the three rollers H H H'. This end of the mandrel is tapered, and has the shoulder j, to form a stop for the end of the tube from which the socket is to be made.

The withdrawing-lever K is connected by the link k to the hand withdrawing-lever K', in front of the machine.

This lever K' moves in the arc Q, and is locked by the notch q in that arc. When thus locked, the workman can use as much force as desirable in pushing the tube-end on to the mandrel, and after the completion of the rolling, the workman, by springing the lever K' sideways out of the notch q, can then operate the lever K, and withdraw the mandrel from the finished socket.

The treadle M is hung upon the bed-plate, with the

counterbalance weight N at the back end, and a foot-pad on the front one. To this treadle are attached the side connecting-links m m, which join the lifting-bearing of the top shaft G and roller H' and cutter I, so that the workman, by placing his foot on the treadle, can cut off and roll the socket, and release the same by removal of his foot.

I am aware that the rolling of metals transversely to the axis of the bar, in the interstice between three rolls, is an old device of long-known use.

I am aware that a machine having rollers disposed as I have described, has been proposed and put in use by F. W. Webb, in England, for rolling and forming sockets or ferrules upon a mandrel supporting the welded collar, which had previously been made from a strip of metal, (see *London Engineer*, vol. xxi, p. 176;)

What I claim as my invention, and desire to secure by Letters Patent, is—

1. The combination of the annular cutter with the swaging-roll, and of these with the supporting-rolls and mandrel, as herein described, for the manufacture of sockets or ferrules of wrought-iron, from tubes previously either but or lap-welded, by cutting off the same, simultaneously with the swaging or closing down upon a mandrel, as hereinbefore described.

2. The arrangement of the mandrel J, in combination with the rolls H H H' and the withdrawing-lever K, substantially as and for the purpose described.
